WINDOW-STAY.

1,142,140.

Specification of Letters Patent. Patented June 8, 1915.

Application filed November 25, 1912. Serial No. 733,386.

To all whom it may concern:

Be it known that we, DELAMAR C. BRIGGS and CLARENCE W. DAVOCK, citizens of the United States of America, residing at Detroit, in the county of Wayne and State of Michigan, have invented certain new and useful Improvements in Window-Stays, of which the following is a specification, reference being had therein to the accompanying drawings.

The invention relates to stays or members for holding swinging windows in different positions of adjustment, and it is the object of the invention—first, to provide means for securely holding a window in each position of adjustment and further for effectively locking the window in closed position.

To this end the invention consists in the construction of the stay and cooperating fittings as hereinafter set forth.

In the drawings: Figure 1 is a perspective view of a swinging window, partly open and provided with the stay. Fig. 2 is a vertical cross section, showing the engagement 25 of the stay bar with the window frame. Fig. 3 is an elevation of a portion of the frame, showing the notches for engaging the stay. Fig. 4 is a vertical section showing the stay arranged to lock the window in closed position. Fig. 5 is a similar view showing a modified arrangement of parts. Fig. 6 is a plan view of Fig. 4. Fig. 7 is a plan view of Fig. 5. Fig. 8 is an elevation of the stay bar. Fig. 9 is a side elevation 35 partly in section taken at right angles to Fig. 3.

A is a window sash or frame provided with a swinging section or transom B, both parts being preferably of metallic construction; C is a stay bar which is pivotally secured to a bracket D at the lower end of the swinging sash, and is notched for engagement with a flange E at the lower edge of the window opening.

45 A notched stay bar such as described can be used to hold the window at different angles by an adjustment which brings different notches in the bar into engagement with the flange E. It has been found however that where the bar is merely notched the swinging sash will not be securely fastened in its different positions of adjustment. We have therefore devised a construction which guards against the possibility 55 of accidental disengagement, comprising an

undercut notch F in the stay, which forms a pointed tooth G adapted to engage with a recess H in the flange E. This recess H may be formed by a round hole bored in the flange, and to guide the stay in relation thereto a notch I is formed in the flange E, with which the edge of the stay bar is in constant engagement. Thus whenever the window is adjusted into a different angular position, the bar C is raised to disengage 60 the tooth G from the recess H, and after adjustment the reengagement of said tooth with the recess will lock the parts from accidental disengagement.

The stay bar is preferably formed of a 70 T section, the stem portion of which is provided with notches F, while at the securing end the head portion of the T is cut away at J to permit the pivotal attachment of the bar between furcations of the bracket D. 75 These furcations are preferably formed by separate plates D' and D'', which are riveted upon opposite sides of the web K of one of the bars of the swinging sash B, as shown in Fig. 8. The bracket D extends sufficiently to permit the stay bar to extend vertically adjacent to the inner side of the sash as shown in Figs. 4 and 5, when the window is to be locked in closed position. It is desirable when the window is closed to 80 prevent any rattling, which we have accomplished by forming an inclined slot C' in the stay C, which engages the pivot D' in the bracket D and permits longitudinal adjustment of the stay thereon. The arrangement is such that when the stay is in vertical 85 position a longitudinal adjustment thereof will cause the inclined edge of the slot C' to operate as a wedge, drawing the swinging sash into tight contact with the flange E of the stationary frame and preventing rattling. The same effect will be produced whether the bar extends downward or upward from the bracket D, as in either case a 90 wedge action is obtained.

For securing the stay bar in this vertical position a keeper is provided which may be either arranged upon the swinging sash as shown in Fig. 4, or upon the stationary sash as shown in Fig. 5. The keeper L is preferably formed of a sheet metal blank, notched to receive the cross section of the T stay bar C, with an entrance slot sufficient to receive only the stem portion of said bar. To engage the bar with this keeper a portion of the 100

95

100

105

110

T head M is notched or cut away at N so as to permit entrance of the bar through the slot in the keeper. The vertical movement of the bar then permitted by the slot 5 C' will engage the head M with the correspondingly fashioned recess in the keeper and will thus positively lock the sash from movement.

The construction of the keeper L' on the 10 stationary sash is similar to the keeper L on the swinging sash, with the exception that the recess for the T head of the stay bar is turned in the opposite direction, and if desired the keeper may be formed in two 15 sections upon opposite sides of this recess, which sections are separately riveted to the metallic bar of the sash.

The free end of the stay bar C is preferably formed with a hook O which may be 20 formed by bending the T head portion of the bar, the stem portion being cut away.

In use, when the swinging sash is open the stay bar C will be turned to extend transversely of the plane of the swinging 25 sash, and in this position will be held by the bracket D from longitudinal adjustment upon the pivot pin D³. Rattling of the parts may be prevented by forming the rounded end of the stay bar of a radius 30 equaling the space between the pivot pin D³ and the bottom of the slot between the furcation of the bracket D; or in other words, the edge of the sash bar to which the members D' and D² are secured. Thus the stay 35 bar will be held from longitudinal movement whenever it is used for holding the sash in open position, but in closed position when it is arranged parallel to the plane of the sash it is free to be adjusted longitudinally 40 of the slot C' and to operate as an anti-rattling wedge as has been already described.

What we claim as our invention is:

1. A window stay comprising a bar having dove-tail notches in the edge thereof, a 45 stationary flange for engaging said notches, having an aperture therein for interlocking with the portion of said bar adjacent to the dove-tail notches.

50 2. A window stay comprising a bar having dove-tail notches formed in the edge portions thereof, a stationary flange for engagement with said notches, having a notch therein for engaging the edge portion of said bar, and an aperture formed beneath said notch for interlocking with the angular edge portion of the notch in said bar.

55 3. The combination with a swinging window sash of a stay bar pivotally attached to 60 said sash and longitudinally adjustable upon its pivot when in parallelism with the

sash, a keeper apertured to correspond to the section of said stay, and having a lateral entrance slot of lesser width, said stay being cut away at one point for engagement 65 with said entrance slot and interlocking with said keeper upon longitudinal adjustment.

4. The combination with a swinging window of a stay therefor, comprising a 70 notched bar having a flanged head, said bar being pivotally attached to said swinging window and adjustable longitudinally upon its pivot when in parallelism with the sash, a keeper apertured to correspond to the 75 cross section of said bar and its flanged head, having an entrance slot of lesser width, said bar having its head portion cut away at one point for engagement with said entrance slot and interlocking with 80 the keeper upon longitudinal adjustment from its entrance position.

5. The combination with a swinging window sash of a stay pivotally attached thereto, and comprising a bar of T-shaped cross 85 section, the stem of said T being provided with a notched edge and the T-shaped head being cut away at one point, a flange with which said notched edge is engaged to hold the window in different positions of angular adjustment, and a keeper for engagement with said bar when in parallelism with said sash, apertured to correspond to the cross section of said bar, and having an entrance slot for engaging said bar at 95 the point where the head is cut away, and means permitting the longitudinal adjustment of said bar when engaged with said keeper to lock the same.

6. The combination with a swinging window sash, of a seat pivotally attached to said sash and provided with a longitudinal slot for engaging the pivot, and a keeper with which said seat is adapted to interlock, 105 said slot being at an angle to the edge of the bar whereby longitudinal adjustment of the seat when in parallelism with said sash will cause a wedging of the sash to its seat.

7. A window stay comprising a bar having notches in the edge thereof and a stationary flange for engaging said notches, having an aperture therein for interlocking with the portion of the said bar, adjacent to the notches when the flange engages said notches. 110

In testimony whereof we affix our signatures in presence of two witnesses.
